SHOE SOLE

Richard B. Johns, R.F.D. 4, Freeport, Maine

Filed July 28, 1964, Ser. No. 31,040

Term of patent 14 years

(Cl. D7—5)

Fig. 1.

FIG. 3.

FIG. 4.

FIG. 6.

FIG. 5.

FIG. 1 is a bottom plan view of a shoe sole showing my new design;

FIG. 2 is a sectional view taken along line 2—2 of FIG. 1;

FIG. 3 is a sectional view taken along line 3—3 of FIG. 1;

FIG. 4 is a sectional view taken along line 4—4 of FIG. 1;

FIG. 5 is a sectional view taken along line 5—5 of FIG. 1;

FIG. 6 is a sectional view taken along line 6—6 of FIG. 1;

FIGS. 3, 4, 5 and 6 are shown on an enlarged scale.

I claim:

The ornamental design for a shoe sole, as shown.
